UNITED STATES PATENT OFFICE.

BRUNNIE W. QUICK, OF BATTLE CREEK, MICHIGAN, ASSIGNOR TO JOHNSON AUTOMATIC SEALER CO., LTD., OF BATTLE CREEK, MICHIGAN.

CONVEYER.

1,427,325.

Specification of Letters Patent. Patented Aug. 29, 1922.

Application filed November 22, 1919. Serial No. 339,908.

To all whom it may concern:

Be it known that I, BRUNNIE W. QUICK, a citizen of the United States, residing at Battle Creek, county of Calhoun, State of Michigan, have invented certain new and useful Improvements in Conveyers, of which the following is a specification.

This invention relates to improvements in conveyers.

10 The main objects of this invention are:

First, to provide an improved conveyer for carton filling and sealing machines in which the cartons are stopped to receive the material and are then advanced and delivered to receiving conveyers.

Second, to provide a conveyer mechanism having these advantages which is simple and durable in structure and automatic in its operation.

20 Further objects, and objects relating to structural details, will definitely appear from the detailed description to follow.

I accomplish the objects of my invention by the devices and means described in the 25 following specification. The invention is clearly defined and pointed out in the claims.

A structure which is a preferred embodiment of my invention is clearly illustrated 30 in the accompanying drawing forming a part of this specification, in which—

Fig. I is a detail plan view showing details of the switch whereby the articles are directed to the two receiving conveyers.

35 Fig. I^A is a detail plan view of a portion of the conveyer in front of the portion shown in Fig. I, showing the stop mechanism.

Fig. II is a detail longitudinal section on 40 a line corresponding to line 2—2 of Figs. I, III and IV.

Fig. III is a detail transverse section on a line corresponding to line 3—3 of Figs. I^A and II.

45 Fig. IV is a detail transverse section on a line corresponding to line 4—4 of Figs. I^A and II.

Fig. V is a detail view partially in section of the switch operating mechanism.

50 Fig. VI is a detail view on a line corresponding to line 6—6 of Figs. I and V, showing further details of the switch operating mechanism.

Fig. VII is a detail inverted view of the

switch shaft and part of its operating connections.

In the drawing, similar reference characters refer to similar parts throughout the several views, and the sectional views are taken looking in the direction of the little arrows at the ends of the section lines.

For convenience in description, I designate the three conveyers of the embodiment of my invention illustrated as the main conveyer and receiving conveyers. The main 65 conveyer comprises a bottom belt 1 and side members 2 and 3 disposed above and at the sides of the belt 1, so that the cartons or packages are carried along by the belt and guided and retained upon the belt by the 70 side members.

The supporting and driving pulleys of the main conveyer belt are not illustrated as their arrangement will be well understood.

The receiving conveyer comprises belts 4 75 and 5 disposed with their upper reaches transversely of and below the upper reach of the main conveyer belt 1 as shown in Figs. I and V.

Side members 6 and 7 are provided for 80 the first receiving conveyer belt 4 and side members 8 and 9 for the second receiving conveyer belt 5. The side members 2 of the main conveyer belt and the side member of the receiving conveyer belt are connected 85 by a curved guide member 10, while the outer side member 3 of the main conveyer belt and the outer side member 9 of the receiving conveyer belt 5 are connected by the curved guide member 11. 90

The side members 7 and 8 are forwardly curved at 12 and 13 respectively, their forwardly curved ends being connected at 14.

A switch 15 is mounted on the rock shaft 16 disposed between the receiving conveyer 95 belts so that the switch may be swung to the position indicated by full lines in Fig. I to guide the articles from the main conveyer to the second receiving conveyer or to be swung across the main conveyer belt 100 as shown by dotted lines in Fig. I to guide the articles from the main conveyer belt onto the first receiving conveyer.

In advance of the switch, I arrange a stop member or gate 17 adapted to swing 105 across the main conveyer belt to stop the cartons indicated at 18. In practice, the cartons are stopped in this position to re-

ceive the material with which the cartons are filled from a filling and weighing machine, such machine, however, not being illustrated, as it forms no part of this invention.

The stop member or gate 17 is carried by a rock shaft 19 having a weighted arm 20 thereon by which its actuating arm 21 is held against the actuating cam 22. 10 This cam is carried by the cam shaft 23 driven from a suitable source not being here illustrated.

This cam shaft is also the driving shaft for the switch actuating means, it being 15 provided with a sprocket 24 connected by the sprocket chain 25 to a sprocket 26 on the stub shaft 27 carried by an arm 28 on the frame.

A switch actuating cam 29 is secured to 20 this shaft 27. This cam 29 acts upon the link 30 slotted at 31 to engage the shaft 27 and provided with a roller 32 coacting with the cam so that the link is given a reciprocatory movement. The link 30 is connected 25 to one arm of the actuating lever 33 pivoted at 34. The other arm of this lever is connected by the link 35 to an arm 36 on the switch pivot or rock shaft 16. This link is slidably arranged through the arm 30 36 as shown in Fig. VII. A spring 37 is provided to act upon the arm. The spring 38 connected to the arm 36 holds the switch yieldingly in one position.

The cam 29 is shaped so that the switch 35 is held in one position during a predetermined period, it swinging to its other position when released by the cam.

With this arrangement of parts the stop member stops the cartons in the filling position, holding them for the desired period 40 in this position. When released they are directed or delivered to one or the other of the receiving conveyors by the switch 12. In practice, these receiving conveyors 45 convey the filled cartons in a double row to a sealing machine, the details of which are not here illustrated as they form no part of this invention.

I have illustrated my improvements in 50 one form in which I have embodied them in practice. I have illustrated only such parts of that embodiment as seemed to me to be required for a clear illustration of my present improvements. It is believed, however, 55 that the disclosure made will enable those skilled in the art to which my invention relates to embody or adapt the same as may be required to meet any requirements in use.

Having thus described my invention, 60 what I claim as new and desire to secure by Letters Patent is:

1. In a structure of the class described, the combination of a main conveyer comprising a bottom belt and coacting side members, a pair of receiving conveyers disposed

transversely of said main conveyer and comprising bottom belts and coacting side members, the upper reaches of the receiving conveyer belts being disposed below and transversely of the upper reach of the main conveyer belt, there being curved guide members extending from the side members of the main conveyer to the outer side members of the receiving conveyers, the front ends of the inner side members of said receiving conveyers being curved forwardly, a switch member pivotally mounted between said receiving conveyers to swing across the main conveyer to guide the articles on to the first receiving conveyer or to swing across 80 and close the first receiving conveyer, a stop member mounted on a rock shaft at the side of the main conveyer to swing across the same in advance of said switch, a cam shaft provided with a cam for actuating 85 said rock shaft, a switch actuating lever, a switch actuating cam, driving connections therefor to said stop member actuating cam shaft, a link support to be actuated by said switch actuating cam connected to said 90 switch actuating lever, a link connecting said switch actuating lever to said switch, and a spring acting on said switch to yieldingly hold it in one position.

2. In a structure of the class described, the combination of a main conveyer comprising a bottom belt and coacting side members, a pair of receiving conveyers disposed transversely of said main conveyer and comprising bottom belts and coacting side members, the upper reaches of the receiving conveyer belts being disposed below and transversely of the upper reach of the main conveyer belt, there being curved guide members extending from the side members of the main conveyer to the outer side members of the receiving conveyers, the front ends of the inner side members of said receiving conveyers being curved forwardly, a switch member mounted to swing across the main conveyer to 100 guide the articles onto the first receiving conveyer or to swing across and close the first receiving conveyer, a stop member mounted at the side of the main conveyer to swing across the same in advance of said 105 switch, and operating connections for said stop member and switch.

3. In a structure of the class described, the combination of a main conveyer comprising a bottom belt and coacting side members, a pair of receiving conveyers disposed transversely of said main conveyer and comprising bottom belts and coacting side members, the upper reaches of the receiving conveyer belts being disposed below and transversely of the upper reach of the main conveyer belt, there being curved guide members extending from the side members of the main conveyer to the outer side members of the receiving conveyers, the front 120 ends of the inner side members of said receiving conveyers being curved forwardly, a switch member pivotally mounted between said receiving conveyers to swing across the main conveyer to guide the articles on to the first receiving conveyer or to swing across and close the first receiving conveyer, a stop member mounted on a rock shaft at the side of the main conveyer to swing across the same in advance of said 125 switch, and operating connections for said stop member and switch.

- ends of the inner side members of said receiving conveyers being curved forwardly, a switch member pivotally mounted between said receiving conveyers to swing across the 40
 5 main conveyer to guide the articles on to the first receiving conveyer or to swing across and close the first receiving conveyer, a switch actuating cam, a stop member operatively associated with said main conveyer in advance of said switch, operating 45
 10 connections for said switch actuating cam to said stop member, a link support to be actuated by said switch actuating cam connected to said switch actuating lever, a link connecting said switch actuating lever to said switch, and a spring acting on said switch to yieldingly hold it in one position.
 15 4. In a structure of the class described, the combination of a main conveyer comprising a bottom belt, a pair of receiving conveyers disposed transversely of said main conveyer and comprising bottom belts, the upper reaches of which are disposed below and transversely of the upper reach of the main 50
 20 conveyer belt, a switch member adjustably mounted so that in one position it closes and in another position guides the articles onto the first receiving conveyer, a stop member mounted on a rock shaft at the side 55
 25 of the main conveyer to swing across the same in advance of said switch, a cam shaft provided with a cam for actuating said rock shaft, a switch actuating lever, a switch actuating cam, driving connections therefor to 60
 30 said stop member actuating cam shaft, a link support to be actuated by said switch actuating cam connected to said switch actuating lever, a link connecting said switch actuating lever to said switch, and a spring acting on said switch to yieldingly hold it in one position.
 35 5. In a structure of the class described, the combination of a main conveyer comprising a bottom belt, a pair of receiving conveyers disposed transversely of said main conveyer and comprising bottom belts, the upper reaches of which are disposed below and transversely of the upper reach of the main 65
 40 main conveyer belt, a switch member adjustably mounted so that in one position it closes and in another position guides the articles onto the first receiving conveyer, a stop member mounted to swing across the main conveyer in advance of said switch, and operating connections for said stop member and switch.
 45 6. In a structure of the class described, the combination of a main conveyer, a pair of receiving conveyers disposed one at the rear of the other, a switch member mounted to swing across the main conveyer to guide the articles onto the first receiving conveyer or to swing across the first receiving conveyer to close the same, an article stop member mounted in advance of said receiving conveyer and operating connections for said stop member and switch.

In witness whereof, I have hereunto set my hand and seal in the presence of two witnesses.
